[57] CLAIM

The ornamental design for a patient aligner for radiography, as shown and described.

DESCRIPTION

FIG. 1 is a front perspective view of a patient aligner for radiography showing my new design in position of use;

FIG. 2 is a front elevational view thereof in storage position;

FIG. 3 is a rear elevational view thereof in storage position;

FIG. 4 is a top plan view thereof in storage position;

FIG. 5 is a bottom plan view thereof in storage position;

FIG. 6 is an end elevational view thereof taken from the left of FIG. 2; and

FIG. 7 is an end elevational view thereof taken from the right of FIG. 2.

The broken line showing in FIG. 1 of a cassette holder is for illustrative purposes only.
